UNITED STATES PATENT OFFICE.

WILLIAM H. MAGEE AND EDGAR MOTT BOTTOME, OF MOUNDSVILLE, WEST VIRGINIA.

DESIGN FOR A COMBINATION SERVING DISH.

Application filed January 13, 1925. Serial No. 12,032. Term of patent 3½ years.

To all whom it may concern:

Be it known that we, WILLIAM H. MAGEE and EDGAR MOTT BOTTOME, citizens of the United States of America, and residents of Moundsville, county of Marshall, and State of West Virginia, have invented a new, original, and ornamental Design for a Combination Serving Dish, of which the following is a specification, reference being had to the accompanying drawings, in which—

We claim:

The ornamental design for a combination serving dish, as shown.

WILLIAM H. MAGEE.
EDGAR MOTT BOTTOME.
